UNITED STATES PATENT OFFICE.

JAMES H. SCHOONMAKER, OF WINONA, MINNESOTA, ASSIGNOR OF FOUR-FIFTHS TO H. D. MORSE AND N. C. GAULT, OF SAME PLACE.

LIGHTNING-ROD.

SPECIFICATION forming part of Letters Patent No. 243,630, dated June 28, 1881.

Application filed April 30, 1881. (No model.)

To all whom it may concern:

Be it known that I, J. H. SCHOONMAKER, a citizen of the United States, resident of Winona, in the county of Winona and State of Minnesota, have invented a new and valuable Improvement in Lightning-Rods; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a cross-section of the rod. Fig. 2 is a side view.

This invention relates to improvements in lightning-rods.

The invention consists of a rod made up of tubes arranged as hereinafter set forth, and particularly pointed out in the claim.

In the annexed drawings, A is a central straight tube, about which are wound spirally the smaller tubes B, close together. All of these tubes consist of a hollow zinc wire, C, covered with sheet-copper D. These are the best metals, but either the wire or covering may be made of any metal.

By this construction a rod is formed of great strength and durability, having good conductivity, and of cheaper cost than ordinary.

Hollow copper wires placed around a straight hollow copper core is not new. A solid central iron core having an encircling copper sheath and solid twisted encircling wires is also old; and a lightning-rod made of an interior and an exterior copper shell and provided with a flat zinc core is also old. Neither of these constructions are claimed hereinafter.

I claim—

In a lightning-rod, the combination, with a straight hollow zinc core covered with sheet-copper, of a series of twisted encircling tubes of zinc covered with sheet-copper, substantially as and for the purposes set forth.

In testimony that I claim the above I have hereunto subscribed my name in the presence of two witnesses.

JAMES H. SCHOONMAKER.
